ATTORNEY

UNITED STATES PATENT OFFICE.

GEORGE A. SWINEFORD, OF CANTON, OHIO.

TRACK-BRACKET.

No. 806,020.

Specification of Letters Patent.

Patented Nov. 28, 1905.

Application filed July 11, 1904. Serial No. 216,021.

To all whom it may concern:

Be it known that I, GEORGE A. SWINEFORD, of Canton, in the county of Stark and State of Ohio, have invented certain new and useful Improvements in Track-Brackets; and I do hereby declare that the following is a clear, full, and exact description thereof, reference being had to the accompanying drawings, and to the numerals of reference 10 marked thereon, in which—

Figure 1 is a view showing a section of the track and brackets connected thereto. Fig. 2 is a detached view of the bracket. Fig. 3 is a detached view of the bracket, showing a slight modification and illustrating a portion of the track in dotted lines. Fig. 4 is a view showing a portion of the track and illustrating the bracket-connecting apertures. Fig. 5 is a longitudinal section of the bracket illustrated in Fig. 3 and a transverse section of the track, showing a hanger located thereon.

The present invention has particular relation to tracks designed to carry what is known as "sliding doors" for barns and other structures.

Similar numerals of reference indicate corresponding parts in all the figures of the drawings.

In the accompanying drawings, 1 represents the track, which is supported at the required height by means of the brackets 2 or their modified form 3, which brackets are secured to the building by means of suitable screws or their equivalents 4. The brackets 35 are each provided with the right-angled portion 5, which right-angled portion is formed of a length sufficient to extend the track 1 from the building a sufficient distance to allow the hangers 6 to move back and forth 40 upon the track without interference. The hangers are of course provided with the traveling wheels 7 and the door properly attached to the hangers 6 in the usual manner. The right-angled flanges 5 are each provided 45 with the spaced tangs 8, which spaced tangs are preferably formed angular and of a size to correspond with the size of the apertures 9, formed in the track 1.

It will be understood that by providing 50 the tangs and spacing said tangs the track is

connected to each bracket at two points in near relation to each other, by which arrangement a rigid connection is made to each bracket, thereby preventing any twisting strain upon the brackets during the time the door is traveling back and forth upon the track 1. Another object desired is that no pivotal movement takes place between the points of attachment of the track to the brackets brought about by any sagging of the track between the points of attachment. By providing two tangs for each bracket and spacing the tangs a shoulder 10 is provided, which shoulder abuts against the face of the track between the apertures 9, thereby assisting in preventing any swinging movement of the outer ends of the flanges 5, by which arrangement there can be no overdue push or pull upon the attaching-flanges of the brackets, thereby removing the push-and-pull strain from the attaching-screws 4.

In use the tangs 8 are passed through the apertures 9 and the extended ends of said tangs swaged, as illustrated in Fig. 5.

Having fully described my invention, what I claim as new, and desire to secure by Letters Patent, is—

An improved article of manufacture, a track and bracket provided with an attaching-flange and an arm or angle portion extended therefrom and provided with spaced tangs and having a track-contact shoulder formed upon the arm portion of the bracket and located between the spaced tangs, and a track provided with spaced apertures corresponding in size and shape with the size and shape of the spaced tangs, and the spaced tangs located through the spaced apertures in the track and the track seated against the shoulder of the bracket-arm and in close contact therewith, substantially as and for the purpose specified.

In testimony that I claim the above I have hereunto subscribed my name in the presence of two witnesses.

GEORGE A. SWINEFORD.
